GILBERT GERRY DAVIS, OF VANCOUVER, BRITISH COLUMBIA, CANADA.

LOG-RAFT.

1,142,239.

Specification of Letters Patent.

Patented June 8, 1915.

Application filed August 5, 1913, Serial No. 783,098. Renewed April 20, 1915. Serial No. 22,716.

To all whom it may concern:

Be it known that I, GILBERT GERRY DAVIS, a citizen of the United States of America, residing at Vancouver, in the Province of British Columbia, Canada, have invented certain new and useful Improvements in Log-Rafts, of which the following is a specification.

This invention relates to a log raft which 10 has been particularly designed for the conveyance of logs in open water where they may be exposed to a rough sea. In the usual practice, the logs are inclosed between two parallel lines of smaller logs known as 15 "boom sticks", which are chained end to end together throughout the length of the raft and are held apart laterally by cross logs, known as "swifters." Within the area inclosed by these connected boom sticks, the 20 logs to be conveyed are floated, and where the water is rough cross logs known as "top 25 swifters" are placed across the logs within the boom and are chain-connected to the boom sticks on each side. While this means 30 may secure the logs in ordinary weather, where exposed to a rough sea the logs are thrown about so much that they get under the inclosing boom sticks and are washed out, and moreover the capacity of the raft 35 is limited to the area inclosed within the boom sticks and swifters. These defects of the existing system I remedy by providing within the boom sticks, and parallel to them, a series of logs which are all connected to 40 one another and to the boom sticks on each side by wire rope or chain. Upon the floor of logs so formed, a load of loose logs may be piled, considerably above the water level, on the buoyancy of the immersed logs themselves and are retained in position by wire 45 rope or chain carried over them and secured to the boom sticks on each side.

The particular construction of the raft is 50 fully described in the following specification, reference being made to the drawings by which it is accompanied, in which:

Figure 1 is a cross section of the raft unloaded showing the manner of connecting the floor logs to one another and to the boom 55 sticks. Fig. 2, a plan of the same. Fig. 3, a cross section of the raft loaded showing the overties. Fig. 4, a plan of the same, and Fig. 5 is a detail of the trip hook connecting the ties to the boom sticks.

55 In these drawings 2 represents the boom sticks which form the outer lateral edges of

the raft on each side, and 3 the "swifters" or cross logs which maintain the parallelism of the boom sticks. The space between the boom sticks 2 is filled with floor logs 4 which are arranged parallel to the boom sticks and are connected to one another and to the boom sticks 2 by a wire rope or chain 5 and 6, each of which is passed alternately over and under these logs and is on each side 60 made fast to the boom sticks 2. These wire rope or chain ties are, as shown in Fig. 1, so passed over and under the logs that each floor log is held between the opposed bights of the connecting ties. The load logs 10 are 65 filled in on this floor of logs 4, as shown in Fig. 3, of the drawings to a height considerably above the water line and strong ropes or chains 11, are passed over them at intervals and are made fast to the boom sticks 2 70 on each side.

The ends of the floor ties 5 and 6 and of the top binders 11 are connected to the boom sticks 2 by a trip hook 8 somewhat as shown in Fig. 5, so that they may be quickly released to allow the logs to float free. These trip hooks 8, which form no essential part 80 of the invention, consist of a hook member 8 which is retained in the holding position by a ring slidable on the link within which 85 the hook is mounted, the withdrawal of which ring frees the hook.

The raft is one that is simply constructed and the logs are strongly tied together in a quantity considerably in excess of the floating area within the boom sticks and will 90 stand a rough sea without loss.

Although described and illustrated as for the conveyance of saw logs, the system is obviously applicable for carrying poles or 95 shingle bolts.

Having now particularly described my invention, I hereby declare that what I claim as new and desire to be protected in by Letters Patent, is:

1. A log raft, comprising the combination with two lines of boom sticks connected at intervals by swifters which maintain them parallel, of floor logs arranged within the boom sticks and connected to them by lines 105 passing alternately under and over the floor logs, and means for securing a load of logs on the boom sticks and floor logs.

2. A log raft, comprising in combination, parallel boom sticks the ends of which are 110 connected across by swifters, floor logs parallel to the boom sticks and connected to

them by lines passing alternately over and under the floor logs, one line passing under while the other passes over, on which floor logs the load logs are placed, and overties 5 across the load logs and connected at each side to the boom sticks by trip hooks.

3. A log raft, comprising the combination with parallel boom sticks, the ends of which are chain-connected together and cross connected by swifters between each pair of ends, 10 floor logs between the boom sticks and parallel to them, said floor logs connected at intervals to the boom sticks by lines passing alternately over and under the floor logs, one 15 line passing under while the other passes over, said lines connected to the boom sticks by trip hooks and overties connected to the boom sticks and passing over the load on the floor logs, the connection on one side being 20 by trip hooks.

4. A log raft, comprising the combination with two sets of parallelly disposed boom-sticks, chains connecting the adjacent ends

of said sticks together, swifters located crosswise between each pair of ends and connected to said chains, floor logs between each pair of boom-sticks and arranged parallel thereto, lines connected to said boom sticks near the ends of the same and passing alternately over and under the floor logs, one line 25 passing under while another passes over, trip hooks and overties connecting said lines to the boom sticks and passing over the load on the floor logs, the connection on one side only being by trip hooks, all being arranged 30 whereby said raft is composed of a plurality of sections flexibly joined together, each section being in itself rigid, substantially as shown and for the purposes described.

In testimony whereof I affix my signature 35 in presence of two witnesses.

GILBERT GERRY DAVIS.
